UNITED STATES PATENT OFFICE.

GEORGE LEWELLYN MORRISON, OF HUDSON, AND ALEXANDER A. FORDON, OF DETROIT, MICHIGAN.

COLLAPSIBLE BOX.

1,090,558.

Specification of Letters Patent. Patented Mar. 17, 1914.

Application filed November 16, 1912. Serial No. 731,731.

To all whom it may concern:

Be it known that we, GEORGE L. MORRISON and ALEXANDER A. FORDON, citizens of the United States, residing, respectively, at 5 Hudson, county of Lenawee, and Detroit, county of Wayne, State of Michigan, have invented certain new and useful Improvements in Collapsible Boxes, and declare the following to be a full, clear, and exact description of the same, such as will enable others skilled in the art to which it pertains to make and use the same, reference being had to the accompanying drawings, which form a part of this specification.

15 This invention relates to collapsible boxes and particularly to those of the type in which the bottom and cover portions are made from a single piece of paper board or other suitable material.

20 An object of our invention is the provision of an improved box of this character, which is simple, strong and durable in its construction, inexpensive of manufacture and capable of being easily and quickly set up 25 and knocked down as desired, and which is provided with means for holding the inner end corners of the cover sides when in closed form.

Another object of our invention is the 30 provision of a single-piece collapsible box of this nature, which has the sides and ends of its body and cover portions so scored as to prevent the weakening effect which is customarily present in boxes of this character having scored folding or collapsing lines, and which enables the box to be easily and quickly collapsed from set-up state.

The invention is fully described in the following specification, and while, in its 40 broader aspect, it is capable of embodiment in numerous forms, a preferred embodiment thereof is illustrated in the accompanying drawings, in which,—

Figure 1 is a plan of the box blank. Fig. 45 2 is a perspective view of one end portion of the box when it is folded into position and before the staples are inserted. Fig. 3 is a perspective view showing the box partially collapsed. Fig. 4 is a plan view of the box 50 collapsed and ready for shipment, and Fig. 5 is a perspective view of the finished box with the cover slightly raised from its closed position.

Referring to the drawings, A designates 55 the body portion, and B the cover portion of

the box, which portions are hingedly connected along the line c. The body A is scored by four lines a, each of which is parallel to one side edge of the body and a distance therefrom equal to the desired height 60 of the box. The crossing of the lines a leaves a gusset 2 at each corner of the body section, which is bisected by a diagonal scoring 3. When the sides and ends of the bottom section are in upright position the gussets 2 fold inward, as shown in Fig. 2, and the securing staples, shown in Figs. 3, 4 and 5, may be inserted through these gussets and the box ends to hold the ends and sides together. The three outside edges of the cover 65 section B of the blank are paralleled by scorings b, distant from the edges a distance equal to the height of box desired, and the crossing of these scorings form gussets 5 that are bisected by diagonal scorings 6. The gussets 5 fold together on the outside 70 of the end portions of the cover, as shown in Fig. 2, and may be stapled together and to the ends of the cover by staples. The portions of the hinge line c without the 75 score lines b are slit, as at 1, to separate the cover ends from the inner gussets 2 of the bottom section.

When the box is in its set-up form the cover section B is intended to fit down over 80 the bottom section A with the front side and ends of the cover section at the outer sides of the respective side and ends of the bottom section. In order to protect the rear 85 ends or corners of the cover ends from injury and also to assist in locking the cover in place on the bottom section, the ends of the bottom section are provided at their lower rear corners with slits 4, which are cut obliquely across such corners in position 90 for the lower rear corners or points of the cover ends to be inserted therein when the box is in closed form, as indicated in Fig. 5. The gussets 2, which are disposed at the slit 95 corners of the bottom section, lap the inner sides of the body ends over at least a portion of the respective slits 4 and coöperate with the ends to form sockets into which the rear corners of the cover ends may be inserted when projected through the slits 4. 100 While the provision of this slit in the manner and for the purpose described may seem of trivial importance it is found in practice to add very materially to the practicability 105 and efficiency of the box, as the rear or free 110

ends of the cover ends are not only protected from injury when inserted within the slits 4 but also assist very materially in locking or securing the cover against opening.

5 The lapping of the gussets 2 over the slits 4 within the box causes such gussets to cooperate with the respective ends of the bottom section to grip the inserted corner portions of the cover and to guide the inserting 10 movements thereof to prevent the cover corners from having contact with goods disposed within the box.

The collapsing of the box is accomplished by providing the ends of the bottom section 15 with diagonal scorings *d*, which extend from the corners of such section in oblique lines to the outer or top edges of the ends, as shown, thus permitting the ends of the bottom section to have outward collapsing 20 movements and the sides of such section to have inward collapsing or folding movements over the bottom of the section, as indicated in Fig. 3. The scoring and folding of the front side and ends of the cover section 25 for collapsing purposes are the reverse of that of the bottom section in that the front 7 of the cover section is provided with the score lines *e*, which extend obliquely from the respective corners in converging 30 relation to the outer edge of such side, as shown in Figs. 1, 3, 4 and 5. This enables the ends of the cover section to collapse inwardly upon the top portion of such section and the front 7 thereof to collapse outwardly, as indicated in Figs. 3 and 4. The 35 cover section is then folded down flat upon the bottom section with its free end projecting beyond the front edge of the bottom section, thus placing the box in flat compact 40 form for shipping or storing. The arranging of the collapsing scorings *d* in the ends of the bottom section and the scorings *e* in the front side of the cover section, or vice versa, provides an exceptionally strong box, 45 when closed, as the tendency of the ends of the cover section to fold inward opposes the tendency of the ends of the bottom section to fold or collapse outward, and such opposing action is augmented by the insertion of 50 the free corners of the cover ends into the slits 4 of the bottom section. The bottom section in the same manner opposes the collapsing action of the cover section.

We wish it understood that our invention is not limited to any specific construction or arrangement of the parts except in so far as such limitations are specified in the claims.

Having thus described our invention,

what we claim as new, and desire to secure 60 by Letters Patent, is,—

1. A collapsible box having hingedly connected bottom and cover sections, the bottom section having an obliquely disposed slit at each lower rear corner thereof and 65 the cover section having the rear ends of its end walls free to provide corners for insertion into said slits when the cover section is closed over the bottom section.

2. A collapsible box having hingedly connected bottom and cover sections, the bottom section having the ends and rear side wall thereof connected at their ends by gussets, which gussets fold inward at the inner sides of the end walls and are secured thereto, and said ends having their lower rear corners provided with obliquely disposed slits which are at least partially covered at 75 their inner sides by said gussets, and the cover section having the rear ends of its end 80 walls free to provide corners for insertion into said slits when the cover section is closed over the bottom section.

3. A collapsible box having hingedly connected bottom and cover sections in a single 85 piece, one section having its end walls provided with oblique scorings to adapt such ends to have outward collapsing movements and the connected side walls to have inward folding movements, and the other section 90 having its side wall provided with oblique scorings to adapt such wall to have outward collapsing movements and the end walls thereof to have inward folding movements.

4. A collapsible box having hingedly connected bottom and cover sections with the end walls of the bottom section adapted to have outward collapsing movements and the side walls of such section to have inward collapsing movements to project the hinged 95 edge of the cover section forwardly over the bottom section, and the cover section having its front wall adapted to collapse outwardly and its end walls adapted to fold inwardly under the top of the cover section, the cover section when collapsed down upon the bottom section having its forward edge projected beyond the forward edge of the bottom section, and the bottom section having its ends projected outwardly beyond 100 the end edges of the cover section.

In testimony whereof, we sign this specification in the presence of two witnesses.

GEORGE LEWELLYN MORRISON.
ALEXANDER A. FORDON.
